UNITED STATES PATENT OFFICE.

FRIEDERICH MÜLLER, OF HARTFORD, CONNECTICUT, ASSIGNOR TO PRATT & WHITNEY COMPANY, OF NEW YORK, N. Y., A CORPORATION OF NEW JERSEY.

LUBRICATOR FOR TAILSTOCK CENTERS.

Application filed April 27, 1921. Serial No. 464,911.

To all whom it may concern:

Be it known that I, FRIEDERICH MÜLLER, a citizen of the United States, residing at Hartford, in the county of Hartford and State 5 of Connecticut, have invented certain new and useful Improvements in Lubricators for Tailstock Centers, of which the following is a specification.

This invention relates to spindle lubricating means and particularly to such a means as applied to a tailstock spindle for lubricating the work supporting center thereof at its point of contact with the work.

The primary object of the invention is 15 to provide a lubricating pump having improved means for operating the same in synchronism with the longitudinal movement of the spindle and center whereby a lubricant is automatically supplied to the 20 center at its work engaging surface upon the engagement of the center with the work.

More specifically, it is an object of the invention to provide a lubricating pump in combination with a tailstock, and an operative connection between the pump and spindle whereby, upon the feeding of the spindle toward the work, the pump is automatically operated to supply a quantity of lubricant to the center at its point of engagement with the work.

With the above and other objects in view, my invention consists in features of construction and operation set forth in the following specification and illustrated in the 35 accompanying drawing. In such drawing annexed hereto and forming a part of this specification, I have shown my invention as embodied in a lathe tailstock of the type illustrated in my Patent No. 1,318,223, dated 40 October 7, 1919, but it will be understood that the invention can be otherwise embodied and that the drawing is not to be construed as defining or limiting the scope of the invention, the claims appended to this 45 specification being relied upon for that purpose.

Referring to the figures of the drawing:

Fig. 1 is a vertical longitudinal sectional view of a tailstock having my invention embodied therein.

Fig. 2 is a cross section thereof on the line 2-2 of Fig. 1, the spindle however not being illustrated.

Fig. 3 is a bottom plan view of the mechanism illustrated in Fig. 2.

Fig. 4 is a detail view taken on line 4-4 of Fig. 2.

Fig. 5 is a fragmentary elevation of the spindle

Fig. 6 is a fragmentary sectional view of the spindle taken on line 6-6 of Fig. 5.

In machines comprising a spindle having a center for rotatably supporting a piece of work, it is very desirable that the center be supplied with a lubricant at its point of contact with the work. The present invention provides means for so lubricating the center and is adapted to operate automatically to supply such lubricant upon engagement of the center against the work. As 70 illustrated in the drawing, I provide a lubricating pump and preferably mount the same on the longitudinally movable spindle. Means is provided in connection with the spindle and the pump piston for operating 75 the latter on a suction stroke during the rearward movement of the spindle and on an oil discharging stroke during the forward movement of the spindle. The mechanism is preferably so constructed as to provide 80 for preventing the flow of oil to the center except when the same is in engagement with the work. The special details of the construction illustrated in the drawing will 85 now be described.

Referring to the drawing, 1 represents the main frame or body of a tailstock, this being adjustably mounted in the usual way on the guideways 2, 2 of a lathe bed 3. The body part of the tailstock can be clamped 90 to the bed by any usual or preferred means such as indicated as a whole by 4. Extending longitudinally through the body of the tailstock is a cylindrical aperture in which is slidably mounted a sleeve 5. Preferably, 95 for reasons which will presently appear, the aperture is formed in a support or spindle 6 which itself is longitudinally movable in an aperture in the main frame of the tailstock.

The aperture of the sleeve 5 is tapered at one end to receive a center 7 in the usual manner. At the other end the aperture of the sleeve 5 is enlarged to receive a coil spring 8 which serves to move the sleeve 105 toward the left. At its inner or left-hand end the spring 8 abuts against a washer 9 positioned within the sleeve, and at its outer or right-hand end the spring abuts against a member or bushing 11 which is adjust- 110

able within the sleeve, preferably being screw threaded. Preferably a bushing 10 is interposed between the spring and the bushing 11. For limiting the movement of 5 the sleeve 5 toward the left there is provided a stop in the form of a cap 12 surrounding the sleeve and engaging a beveled surface thereof, this cap having threaded engagement with the spindle 6.

10 With the parts in the positions shown, the sleeve 5 is held in its left-hand position in engagement with the cap 12, but it is free to yield toward the right against the action of the spring 8 when pressure is applied to the 15 center 7. The spring pressure can be adjusted by turning the bushing 11. The adjustment shown, with the sleeve 5 held by the spring, is that which is ordinarily desirable for turning light slender work. For 20 heavier work, when no yielding of the tailstock center is desired, the bushing 11 is turned and moved into firm engagement with the right-hand end of the sleeve 5, thus forcing the sleeve into firm engagement with 25 the cap 12. This locks the sleeve and holds it rigidly against any movement with respect to the spindle 6.

30 Preferably, for preventing the sleeve 5 from turning in the spindle 6, there is provided a screw 13 in the spindle 6 which projects into a keyway in the sleeve 5.

35 It will be observed that there is an opening entirely through the outer part of the sleeve 5 thus making it possible to insert a rod for driving out the center 7 when necessary.

40 When the tailstock is to be used as a part of an automatic lathe, means is provided for automatically moving the spindle 6 to bring 45 the center 7 into and out of engagement with the work. As illustrated, a collar 14 is slidably mounted on the spindle 6, having adjustable frictional engagement therewith by means of a suitable friction shoe, as 50 shown in my Patent No. 1,318,223, dated Oct. 7, 1919. The collar 14 is connected with a longitudinal rod 16 which is adapted to be moved by the lathe mechanism at the proper times. When the rod 16 is moved toward the left it carries the collar 14 with it and the collar 14 moves the spindle 6 with the center until the center engages the work. Thereafter the collar 14 slides on the spindle. The frictional resistance at 55 should be less than the resistance offered by the spring 8, so that the spindle 6 will not be moved relatively to the sleeve 5.

60 A lever 17 is pivotally mounted on the main frame of the tailstock and at its right-hand end carries a roller 18 adapted to engage a cam surface 19 formed on the collar 14. The lever 17, at its right-hand end, is adapted to engage a shoe 20 which is in contact with the spindle 6. The continued 65 movement of the collar 14 toward the left

forces the cam surface 19 under the roller 18, thus swinging the lever 17 in the counter-clockwise direction and pressing the shoe 20 into firm engagement with the spindle 6. In this way the spindle is firmly held 70 against any return movement and the center 7 is firmly held in engagement with the work and is permitted to move, if at all, only against the resistance of the spring 8. When the rod 16 moves the collar 14 in the 75 other direction toward the right, the lever 17 is released, thus releasing the pressure on the spindle 6. Further movement of the collar 14 causes the spindle 6 to be moved toward the right, thus withdrawing the 80 center from engagement with the work.

85 The mechanism thus far described comprises substantially the subject matter of my aforesaid Patent No. 1,318,223. The mechanism illustrating an embodiment of the present invention will now be described.

A pump represented at 21 is adapted to supply a lubricant to the center 7 of the tailstock at its work engaging surface. I preferably mount this pump on the spindle 90 6 and provide means adapted to operate the pump upon the reciprocation of the spindle. As illustrated, the pump cylinder is formed in a yoke or collar 22 secured to the spindle by means of a clamping screw 23. 24 represents an oil cup or reservoir screw threaded into the cylinder at 25. A valve 26 normally held closed by means of a spring 27 and surrounding the valve stem is provided at the lower ends of ports 28. The oil cup 95 100 may be filled by removing a closure plug 29 therein.

105 The piston 30 within the cylinder is normally held in its inward position by means of a spring 31 surrounding the piston rod 32 between the piston and a closure plug 33 screw threaded into the cylinder. An arm 34 pivoted at 35 to a pair of lugs 36 on the yoke is forked at its free end to engage 110 against check nuts 37 on the piston rod. 38 represents a wedge member screw threaded into the body member 1 and freely slid able in a bore 39 in the yoke in a position to engage a projecting portion 40 on the arm 34 as the spindle is reciprocated.

115 A port 41 leads from the pump cylinder through the yoke to an elongated recess 42 on the inner surface of the yoke. 43 and 44 represent ports extending from the recess 42 through the spindle 6. 45, 46, and 47 represent ports extending through the sleeve 5 and center 7 to the work engaging end of the latter. Circumferential recesses 45^a and 46^a are preferably provided around the sleeve 5 and center 7 in connection with the ports 45 and 46 therein. Ports 43 and 44 are screw threaded and either of such ports is adapted to be closed by means of a plug 48. With the bushing 11 set in the position shown in Fig. 1 wherein the sleeve 5 has 120 125 130

a sliding movement within the spindle 6, the port 43 should be closed by the plug 48 and the port 44 left open. When the bushing 11 is set into engagement with the sleeve 5 so that the latter has no sliding movement within the spindle 6, the port 44 should be closed by the plug 48 and the port 43 left open. The purpose of such construction is herein-after described.

With the mechanism adjusted as shown in Fig. 1, the operation is as follows: As the spindle 6 is withdrawn from the work, the projecting portion 40 on the arm 34 engages the wedge 38 and draws the piston 30 outwardly thus drawing a quantity of oil through the valve 26 into the cylinder. As the spindle is moved forwardly toward the work the spring 31 forces the piston inwardly and compresses the oil in the cylinder and ports 41 to 45. However, since the port 43 is closed by the plug 48 no oil can enter the center ports until port 44 comes into communication with port 45. Spring 8 normally keeps the sleeve 5 in the forward position illustrated in Fig. 1. However, when the center engages against the work further movement of the spindle 6 will slide the same over sleeve 6 and thereby bring ports 44 and 45 into register, whereupon oil will pass into the several ports to the work engaging end of the center 7. When the bushing 11 is adjusted to engage directly against the sleeve 5 so that the sleeve has no longitudinal movement in the spindle 6, the pump cylinder is at all times in communication with the center port 47 through the port 43, port 44 being closed by the plug 48.

What I claim is:

1. In a machine tool, the combination of a spindle, means for moving the spindle longitudinally, a lubricating pump, an oil conduit leading from the pump to the spindle, and means controlled by the longitudinal movement of the spindle and operative on the pump for discharging a quantity of oil from the pump to the spindle.
2. In a machine tool, the combination of a spindle, means for moving the spindle longitudinally, a lubricating pump, an oil conduit leading from the pump to the spindle, and means controlled by the longitudinal movement of the spindle and operative on the pump piston for drawing a charge of oil into the pump as the spindle recedes and for discharging a quantity of oil from the pump to the spindle as the spindle advances.
3. In a machine tool, the combination of a spindle, means for moving the spindle longitudinally, a lubricating pump, an oil conduit leading from the pump to the spindle and means controlled by the longitudinal movement of the spindle and operative on the pump piston for drawing a charge of oil into the pump as the spindle recedes and for discharging a quantity of oil from the

pump to the spindle as the spindle advances, the movement of the spindle in one direction acting positively on the piston to move the same.

4. In a machine tool the combination of a spindle, means for moving the spindle longitudinally, a lubricating pump, an oil conduit leading from the pump to the spindle, means operating positively on the pump piston by the longitudinal movement of the spindle for drawing a charge of oil into the pump as the spindle recedes, and a spring operative on the piston to move the same in the opposite direction to discharge a quantity of oil from the pump to the spindle as the spindle advances.

5. In a tailstock, the combination of a body member, a center supporting spindle slidably mounted therein, a lubricating pump mounted on the spindle, an oil conduit leading from the pump through the spindle to the tailstock center, and means controlled by the reciprocating movement of the spindle for operating the pump to force oil through the conduit to the center.

6. In a tailstock, the combination of a body member, a center supporting spindle slidably mounted therein, a yoke mounted on the spindle, a lubricating pump mounted on the yoke, an oil conduit leading from the pump through the yoke and spindle to the tailstock center, and means comprising a cam on the body member for operating the pump to force oil through the conduit to the center upon reciprocating movement of the spindle.

7. In a tailstock, the combination of a body member, a spindle slidably mounted therein, a work supporting center mounted in the spindle, means for moving the spindle longitudinally, a lubricating pump, and means for automatically supplying a quantity of lubricant from the pump to the center at its point of contact with the work only after the center has engaged the work.

8. In a tailstock, the combination of a body member, a spindle slidably mounted therein, a center supporting sleeve slidably mounted in the spindle, the spindle and sleeve each having a duct therein, and a source of lubricant supply in communication with the duct in the spindle, the relative arrangement of the two ducts being such that as the sleeve slides rearwardly in the spindle the two ducts come into register whereby a charge of oil is discharged into the sleeve.

9. In a tailstock, the combination of a body member, a spindle slidably mounted therein, a center supporting sleeve slidably mounted in the spindle, a spring normally holding the sleeve in a forward position in the spindle, the spindle and sleeve each having a duct therein, and a source of lubricant supply in communication with the duct in

the spindle, the relative arrangement of the two ducts being such that as the sleeve slides in the spindle against the action of the spring, the two ducts come into register whereby a charge of oil is discharged into the sleeve.

10. In a tailstock, the combination of a body member, a spindle slidably mounted therein, a center supporting sleeve slidably mounted in the spindle, a spring normally holding the sleeve in a forward position in the spindle, the spindle and sleeve each hav-

ing a duct therein, a pump in communication with the duct in the spindle, the relative arrangement of the two ducts being 15 such that as the sleeve slides in the spindle against the action of the spring, the two ducts come into register whereby a charge of oil is discharged into the sleeve, and means operated by the sliding movement of 20 the spindle for operating the pump.

In testimony whereof, I hereto affix my signature.

FRIEDERICH MÜLLER.
